CLAIM

I claim, the ornamental design for a cooking pan for use in heating cookers, as shown and described.

DESCRIPTION

FIG. 1 is a top and front perspective view of a cooking pan for use in heating cookers, showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof; and,

FIG. 8 is a reference perspective view showing that the cooking pan for use in heating cookers is applied to an infrared heating cooker.

The broken lines shown in the drawings are for illustrative purposes only and form no part of the claimed design.
